CLAIM

The ornamental design for a mulch blanket anchor, as shown and described.

DESCRIPTION

FIG. 1 is a top, front and left side perspective view of a mulch blanket anchor showing our new design;
FIG. 2 is a left side elevational view thereof, the right side being a mirror image of that shown;
FIG. 3 is a front elevational view thereof;
FIG. 4 is a rear elevational view thereof; and
FIG. 5 is a top plan view thereof.
